UNITED STATES PATENT OFFICE.

HARRY ABRAMSON, OF PHILADELPHIA, PENNSYLVANIA.

GAS-HEATED IRON.

1,060,572.

Specification of Letters Patent. Patented May 6, 1913.

Application filed November 6, 1912. Serial No. 729,839.

To all whom it may concern:

Be it known that I, HARRY ABRAMSON, a citizen of the United States, residing in the city and county of Philadelphia, State of Pennsylvania, have invented a new and useful Gas-Heated Iron, of which the following is a specification.

This invention relates to gas heated sad irons and has for an object to provide an iron in which the ironing surface is evenly and uniformly heated at all points and wherein the heat distributing means are so arranged and constructed as to prevent localization of the heat at one or more points.

15 In gas irons, as heretofore constructed, it has been found in practice that where the burner and its adjuncts are located at one end or the side of the iron body, it has been extremely difficult, if not impossible, to cause 20 the flame to evenly distribute the heat over the bottom of the iron and in fact such devices are more highly heated at the heel portion of the iron than at the toe. It is very important that the toe of the iron should 25 be heated to the same temperature as the heel of the iron, since it is the toe which first contacts with the damp articles and it is therefore subjected to an initial chilling so that it is preferable that the toe should 30 be heated, if anything, to a higher temperature than the rest of the bottom of the iron.

It is an object of my invention to overcome the foregoing defects and provide a 35 burner mechanism which is so located with respect to the iron body that the heat is distributed uniformly over the ironing surface and the flame is just as effective for heating one part as another.

It further consists of other novel features 40 of construction, all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities 45 of which my invention consists can be variously arranged and organized and that my invention is not limited to the precise arrangement and organization of these instrumentalities as herein shown and described.

50 Figure 1 represents a sectional elevation

of a gas iron embodying my invention. Fig. 2 represents a plan of the body of the iron with the top and certain of the burner adjuncts removed. Fig. 3 represents a perspective of the heat deflector. Fig. 4 represents a perspective of the burner. Fig. 5 represents the bottom of the burner showing the arrangement of the burner outlets. Fig. 6 represents a perspective of the top of my novel iron and its adjuncts. Fig. 7 represents a perspective of the top plate. Fig. 8 represents a perspective of a modified form of burner. Fig. 9 represents a section on line $x-x$ of Fig. 1.

Similar numerals of reference indicate 70 corresponding parts in the figures.

Referring to the drawings:—1 designates the body of the iron which is preferably hollow and substantially elliptical in form so that the iron may be operated in either 75 direction and thus reduce the chilling effect on the toe of the iron in its initial contact with the damp articles being ironed.

2 designates a plurality of inlet openings distributed at suitable intervals adjacent 80 the bottom 3 of the iron and serving as a means to introduce air into the body 1 in order to complete the combustion of the gases and allow all the available heat to be abstracted therefrom. The upper portion of 85 the iron body 1, as here shown, is provided with a longitudinal recess 4 on each side thereof which serve as outlets for the products of combustion and prevent a gas cushion being formed in the body of the iron 90 beneath the top plate 5.

6, 7 and 8 designate a plurality of lugs preferably formed integral with the bottom 3 and projecting a suitable distance within the hollow body to serve as heat 95 retainers for distributing the heat uniformly over the bottom 3 and thereby maintaining the bottom evenly heated at all points and it will further be noted that the lugs 7 preferably cover a larger area than either of the 100 lugs 6 or 8 in order to conduct more heat to the toe end of the iron where it is needed to overcome the aforesaid chilling effect.

The top plate 5, in the present instance, 105 is detachably connected to the iron body 1 by providing at each end an open ended slot 9 adapted to straddle a threaded pin 10 which screws into the threaded opening 11 provided at each end of the body 1 for the 110

purpose. These pins 10 are each bent outwardly and downwardly in order to contact with the upper surface of the top plate 5 and securely clamp the same in its normal 5 position upon the iron body 1.

12 designates the handle of the iron which, as here shown, is mounted on a suitable frame 13 and secured to the top plate 5 by means of screws 14 or other suitable fastening devices. The handle is preferably spaced 10 from the plate 5 by lugs 35 and the boss 36 so that heat radiation is reduced. In connection with the top plate 5 it will be noted that the same is provided with a transverse opening 15 disposed at substantially the center and serving as a means to introduce the gas carrying conduit which will now be described.

16 designates a suitable pipe fitting adapted 20 to be inserted within the opening 15 preferably tapered for frictional engagement with a washer 21 which seats, in the present instance, on the plate 5. This fitting terminates in a threaded end 17 adapted for 25 engagement with the tubular neck 18 of the burner 19 and it will be noted that this neck passes through a shield 20 as will be seen from Fig. 1. In order to prevent turning movement of the burner 19, which would 30 cause relative displacement of the parts, I have preferably formed a pair of lugs 22 on the said neck 18 which are adapted to fit recesses 23 formed in the boss of the opening 15 and in the sides of the opening of the 35 shield 20 and the action should be readily apparent.

The burner 19, in the present instance, is formed as a hollow member having lateral 40 extensions 24 for the purpose of directing the flame to all the essential parts of the floor of the bottom 3. The lower surface 25 of the burner is provided with a plurality of perforations 26 through which the flames pass and impinge directly against the bottom of the iron and these perforations are 45 arranged, in the present instance, to most effectively distribute the heat over the proper surface. It will be noted that the burner 19 is suspended from the fitting 16 50 so that there is a sufficient space between the bottom 3 of the iron and the lower surface 25 of the burner to permit the products of combustion to pass out therefrom and enter an auxiliary heating chamber 27 formed beneath the shield 20. This latter element is 55 supported by suitable pins 28 here shown as forming a part of the burner and serving as spacer elements between the said burner and the said shield. The shield 20, as here 60 shown, is provided with outwardly and downwardly flaring side walls 29, the edges of which closely fit the inner walls of the body 1 of the iron and adjacent the lower portion of the side walls 29 are a plurality 65 of openings 30 whereby it will be understood

that the said shield 20 serves to deflect the heat downward against the bottom of the iron, while the openings 30 therein are of sufficient number and size as to prevent the improper or too rapid escape of the waste products and yet permit a suitable amount thereof to pass through the recesses 4 in the body 1.

31 designates a bushing, preferably, of asbestos or other non-heat conducting material, interposed between the plate 5 and the shield 20, whereby the top of the iron is further safeguarded from the radiation of heat.

32 designates a Bunsen attachment of ordinary construction through which air and gas properly mixed are led to the fitting 16.

In Fig. 8 I have disclosed another form of burner which is particularly adapted for the burning of natural gas and wherein the 85 burner perforations or openings 33 are disposed longitudinally thereof and arranged in a series of rows on the lower portion of the curved burner face.

In the operation of the device the gas 90 enters the fitting 16 by way of the pipe 34 after, of course, having passed through a suitable Bunsen regulator, and is delivered to the interior of the burner 19 and discharges through the openings 26. Here it 95 is ignited and burns with the desired heat producing flame and substantially all the available heat is extracted by reason of the admission of air through the inlet openings 2. The heat from the flame rises within the 10 shield 20 and is deflected and radiated to the outer edge of the floor of the bottom 3 thus heating the entire inner surface of the bottom and making it possible to obtain a uniform distribution of the heat on the 10 ironing surface. The waste products discharge from the heating chamber 27, pass through the openings 30, and mingle with the outside air by way of the exhaust recesses 4.

It will now be apparent that I have devised a complete unitary structure, simple in construction, effective in operation and one in which substantially all the heat is extracted and taken up by the bottom of the 11 iron. It will further be noted that the provision of the shield 20 with its diverging walls 29 forms a heat chamber for deflecting any heat, which would otherwise be lost, to the edges of the iron body and which 12 materially assists in obtaining an even heat. It will be further noted that, by introducing the gas at substantially the center of the iron, there is a more equal distribution 13 of the heat than would be obtained if the gas were introduced at one end or side of the iron as is a common practice. Further, by this construction, the gas tube is located at substantially the vertical axis of the iron and will therefore have a minimum amount

of movement and will not continually be in the way of the user and obstruct the path of the iron during an ironing operation.

By my novel clamping means, connecting the burner and its adjuncts with the plate 5, it is possible, by simply giving the threaded pins 10 a partial turn, to remove the said plate and burner as a unit, thus making all the parts readily accessible for cleaning or 10 repairs.

It will now be apparent that I have devised a novel and useful construction of a gas heated iron which embodies the features of advantage enumerated as desirable in the 15 statement of the invention and the above description, and while I have, in the present instance, shown and described a preferred embodiment thereof which has been found in practice to give satisfactory and reliable 20 results, it is to be understood that the same is susceptible of modification in various particulars without departing from the spirit or scope of the invention or sacrificing any of its advantages.

Having thus described my invention, what 25 I claim as new and desire to secure by Letters Patent, is:

1. In a device of the character stated, a hollow body having a plurality of openings 30 adjacent the bottom thereof, a burner located in said hollow body, having a plurality of perforations therein adapted to direct a flame or flames downwardly upon said bottom, a shield having downwardly extending 35 side walls partially inclosing said burner and forming a heating chamber, said walls having passages therein, means to introduce a combustible mixture to said burner, and means to discharge the products of combustion to the exterior of said hollow body.

2. In a device of the character stated, a hollow body having a plurality of openings adjacent the bottom thereof, a plurality of lugs formed on the bottom of said body and 45 on the inside thereof, a burner juxtaposed with respect to said lugs and having a plurality of perforations adapted to direct a flame against said lugs, a shield having downwardly extending and outwardly flaring side walls partially inclosing said burner and having a plurality of openings therein, said shield forming a heating chamber, means to introduce a combustible mixture to said burner, and means to discharge 50 the products of combustion to the exterior of said hollow body.

3. In a device of the character stated, a hollow body having a plurality of openings adjacent the bottom thereof and a longitudinally disposed recess in each side, a plate, detachably secured to said hollow body, forming a top therefor, a burner juxtaposed with respect to the bottom of said hollow body, said burner having ends situated 60 adjacent the toe portions of the body.

and having laterally extending intermediate members and said burner having a plurality of perforations therein adapted to direct a flame or flames to the bottom of said body, a shield in said hollow body forming a heating chamber partially inclosing said burner, and means passing through said top plate for introducing a combustible mixture into 70 said burner.

4. In a device of the character stated, a hollow body, a burner located therein, said burner having ends situated adjacent the toe portions of the body and having laterally extending intermediate members and having a plurality of perforations adapted to direct a flame or flames to the bottom of said body, a shield in said hollow body forming a heating chamber partially inclosing said burner, means to conduct air to said heating chamber, and means to discharge 75 the products of combustion to the exterior of said hollow body.

5. In a device of the character stated, a hollow body, a burner located therein, said burner having ends situated adjacent the toe portions of the body and having laterally extending intermediate members and having a plurality of perforations adapted to direct a flame or flames to the bottom of said body, means to maintain said burner in fixed relation to said body, a shield in said hollow body forming a heating chamber partially inclosing said burner, a gas inlet to said burner projecting exterior of said hollow body, means to introduce air to said heating chamber, and means to discharge the products of combustion to the exterior of said hollow body.

6. In a device of the character stated, a hollow body, a burner located therein, said burner having ends situated adjacent the toe portions of the body and having laterally extending intermediate members and having a plurality of perforations adapted to direct a flame or flames to the bottom of said body, means to hold said burner from said bottom, a gas inlet to said burner projecting exterior of said hollow body, said inlet being located at substantially the center of the top of said body, a shield in said hollow body forming a heating chamber partially inclosing said burner, means to admit air to said heating chamber, and means to conduct the products of combustion from said heating chamber to the exterior of said hollow body.

7. In a device of the character stated, a hollow body, a burner located therein, said burner having ends situated adjacent the toe portions of the body and having laterally extending intermediate members and having a plurality of perforations adapted to direct a flame or flames to the bottom of said body, a plate detachably carried by said body and forming a top therefor, a shield in said hollow body forming a heating chamber par- 125 130

tially inclosing said burner, a gas inlet fitting having communication with the interior of said burner and means to secure said fitting, said top plate, said burner, and said shield together, whereby said elements may be removed as a unit from said hollow body.

8. In a gas iron, the combination of a body, a burner therein having ends situated adjacent the toe portions of said body and 10 having laterally extending intermediate members, said burner having a hollow neck communicating with the interior of the burner at substantially the center thereof and intermediate the lateral extensions, and 15 said burner having perforations for directing the flame against the bottom of the iron, and means for suitably supporting said burner in said body.

9. In a gas iron, the combination of a 20 body, a burner therein provided with a tubular neck having lugs thereon, a shield having an opening therein adapted to receive said neck and having recesses to receive said lugs, a top plate for said body having an opening 25 adapted to receive said neck, and having recesses adapted to receive a suitable portion of said lugs, and means for supporting said burner with respect to said body.

10. In a gas iron, the combination of a 30 body, a plate forming a top for said body, having an opening therein, a burner located in said body, a gas inlet fitting communicating with said opening and secured to said

burner, to serve as a support therefor, and auxiliary means on said burner in engagement with said top plate, whereby the parts are suitably held together and relative movement thereof is prevented.

11. In a gas iron, a body, a burner therein, a tubular neck rising from said burner, said body having a top plate with an opening therein in which said neck is situated, a boss rising from said top plate at said opening, a handle having a base with an opening 40 therein receiving said boss, a washer resting 45 on said boss and base, a fitting entering said neck and adapted to tighten against said washer, and means connecting said base with said top plate.

12. In a gas iron, a body, a burner therein, a tubular neck rising from said burner, said body having a top plate with an opening 50 therein in which said neck is situated, a boss rising from said top plate at said opening, screw threaded lugs on said top plate, a 55 handle having a base with an opening therein receiving said boss, a washer resting on said boss and base, a fitting entering said neck and adapted to tighten against said washer, and means connecting said base with 60 said top plate on said lugs.
